UNITED STATES PATENT OFFICE.

JOSEPH TITCHETT, OF WARRINGTON, ENGLAND.

GAS-STOVE.

SPECIFICATION forming part of Letters Patent No. 643,755, dated February 20, 1900.

Application filed January 23, 1899. Serial No. 703,138. (No model.)

To all whom it may concern:

Be it known that I, JOSEPH TITCHETT, a subject of the Queen of Great Britain, residing at Warrington, in the county of Lancaster, England, have invented certain new and useful Improvements in Gas-Stoves, of which the following is a specification.

This invention relates to improvements in the arrangement and construction of gas-stoves for cooking purposes, and is designed for the purpose of heating the oven with the least expenditure or loss of heat.

The invention will be fully described with reference to the accompanying drawings.

Figure 1 is a front sectional elevation of the stove. Fig. 2 is a side sectional elevation. Fig. 3 is a plan with the top plate removed, showing the top of the oven. Fig. 4 is a plan from below with the bottom plate removed, showing the bottom of the oven.

The stove is constructed with an interior chamber or oven A, into which no waste or unconsumed gas can enter. The oven A is surrounded on all sides with a number of 25 passages or flues through which the heated gases or other products of combustion are conducted or caused to circulate, so as to pass in succession over the bottom, top, and sides of the oven. The oven can be made in 30 one casting or in sections, as required, and can also be made of sheet-iron.

Beneath the bottom *a* of the oven A is constructed a combustion-chamber B with a bottom plate C, provided with a slot *c*, through 35 which the gas jets or flame from a burner D pass and impinge upon the bottom *a* of the oven near the front. The combustion-chamber extends to the back of the oven and at the sides is inclosed by the two side plates *b*. 40 At the back of the oven is a vertical flue or passage E, extending the full width and height of the oven and opening into a horizontal flue or passage F, constructed over the top of the oven A.

45 At both sides of the oven A are constructed a number of vertical flues or passages G G' G² G³ and H H' H² H³. The flues or passages G G' G² G³ are formed by a number of vertical ribs *g* *g'* *g²* *g³* and *h* *h'* *h²* *h³*. These ribs 50 are cast on the inner side of the external casting K and fit into ribs or grooves *a'* *a²* *a³* *a⁴*, cast upon the external side of the walls of

the oven A, a tight joint being formed by means of asbestos or other non-combustible packing. The bottom of the vertical side 55 flues or passages is formed by a horizontal rib L. The vertical ribs *g* *g²* *h* *h²* have a passage beneath them, and the vertical ribs *g'* *g³* *h'* *h³* have a passage above them to cause the heated gases to pass up and down in zigzag 60 fashion in contact with the sides. The passages and flues are inclosed by an outer casting K, formed of two plates *k* *k'*, with a space between them packed with a non-conducting packing K', such as slag-wool or asbestos, to 65 prevent radiation of heat.

An outlet or exhaust aperture P is formed near the top of the back plate and is fitted with a damper R to close it, the damper being operated or controlled by a rod or handle *r*. 70 An aperture *p* is also made in the oven top, opened and closed by a damper *p'*. The damper *p'* is also operated by the rod *r*. The aperture *p* is formed in the top of the oven A, through which the heated gases can be permitted to enter the oven to heat it or dry it or to allow the escape of steam. This aperture is closed by a damper or shutter *p'*.

A lower chamber A', with shelves *a²*, may be formed below the burner D to heat or maintain the heat of articles placed therein.

Boiling, grilling, or other burners D' may be placed above the top plate of the stove with a suitable frame S. The frame S is mounted upon four legs *s*, one at each corner, a space being thus formed around the grilling or roasting space, which allows of easy access thereto at any side of the stove.

The grilling-burner D' is made with two longitudinal tubes, with apertures *d'*. 90

In operation the heated gases from the flame of the burner D pass through the combustion-chamber B, along the under side of the oven A, up the back flue E, along the horizontal flue F, in contact with the top of 95 the oven, and down through the front corner flues G H, and up and down through the flues G' G² G³ and H' H² H³ in zigzag fashion against the sides of the oven.

What I claim as my invention, and desire 100 to protect by Letters Patent, is—

A gas-stove comprising in its construction the oven A the combustion-chamber B the bottom plate C provided with a slot *c* inclos-

ing the combustion-chamber, the burner D the vertical flue E at the back of the oven the horizontal flue F on top of the oven the side flues G G' G² G³ and H H' H² H³ the vertical ribs g g' g² g³ and h h' h² h³ inclosing the vertical sides flues the outer casing K comprising the plates k k' and the non-conducting packing K' substantially as described.

In witness whereof I have hereunto signed my name in the presence of two subscribing witnesses.

JOSEPH TITCHETT.
